CLAIM

The ornamental design for a beverage container closure, as shown and described.

DESCRIPTION

FIG. 1 is a perspective view of a beverage container closure showing my design.

FIG. 2 is a front elevation view of the beverage container closure of FIG. 1.

FIG. 3 is a side elevation view of the beverage container closure of FIG. 1.

FIG. 4 is a rear elevation view of the beverage container closure of FIG. 1.

FIG. 5 is another side elevation view of the beverage container closure of FIG. 1.

FIG. 6 is a top plan view of the beverage container closure of FIG. 1.

FIG. 7 is a bottom plan view of the beverage container closure of FIG. 1.

FIG. 8 is another perspective view of the beverage container closure of FIG. 1.

FIG. 9 is another perspective view of the beverage container closure of FIG. 1; and,

FIG. 10 is another perspective view of the beverage container closure of FIG. 1.

The dashed lines shown in the drawings illustrate portions of the beverage container closure that are not claimed and thus form no part of the claimed design. The shading lines shown in the drawings represent the three-dimensional contour of the claimed design and are not intended to indicate surface decoration.
